UNITED STATES PATENT OFFICE.

HERBERT N. KILBY, OF CLEVELAND, OHIO.

FILTER.

1,211,859.

Specification of Letters Patent.

Patented Jan. 9, 1917.

Application filed August 31, 1915. Serial No. 48,166.

To all whom it may concern:

Be it known that I, HERBERT N. KILBY, a citizen of the United States, residing at Cleveland, in the county of Cuyahoga and State of Ohio, have invented certain new and useful Improvements in Filters, of which the following is a specification.

The present invention is related to filters wherein various types of fluids may be cleansed or filtered by a circulation there-through. In this connection, it may be stated that my filter is designed especially for use in collecting and filtering out sediment or caking material from such liquors as are produced in the manufacture of sugar.

The main object of my invention resides in the provision of a novel type of lock whereby the movable parts forming the inclosing casing structure may be securely clamped together and held in such clamped position. This new type of lock preferably takes the form of toggle lever means for moving the locking member used both into and out of its operative position of engagement with the movable member.

Another object of my invention also resides in a structure whereby the locking member used is given such movement during its unlocking action that the locking member itself is moved laterally away from its holding position and then is swung outwardly to a position out of all possible interference with the movable casing part. 35 Also, a further feature resides in so constructing and arranging this locking structure so that it is swung out of the path of the discharged cake as it drops from the filter plates.

Still a further object of my invention resides in a counterweight structure so arranged that the movable part of the casing may be manually operated with considerable ease.

Further objects of my invention will become more apparent from the following detailed description of the accompanying drawings wherein is shown the preferred embodiment of my invention.

In these drawings, similar characters of reference designate corresponding parts, and Figure 1 is a side elevation of a filter press with my invention applied thereto, Fig. 2 is a rear elevation of the structure shown in Fig. 1, Fig. 3 is a transverse cross section showing the movable part of the

casing swung to its inoperative position, Fig. 4 is an enlarged detail of my lock shown in connection with portions of the casing, Fig. 5 is a rear elevation of the structure shown in Fig. 4, Figs. 6, 7, 8, 9 and 10 are detail views in perspective of the various elements comprising my improved lock, and, Fig. 11 is a detail view of one end of the locking member shown assembled and also shown partially in section.

The type of filter illustrated comprises an upright back plate 1 supported in any suitable manner upon suitable end standards 2. This back plate is provided along its upper edge with suitable bearings 3, in which a shaft 4 is journaled. Co-operatively mounted with respect to this back plate and pivotally mounted about the shaft 75 4 by means of the hinge structure shown at 5, is a semi-oval hood member 6. This hood member and the back plate co-operate to form an inclosing casing structure for the filter elements designated generally by the reference numeral 7 and which filter elements are so constructed that the cake or sediment is filtered out of the juice in the usual manner. Liquor is introduced to the interior of the casing through the inlet pipe 85 shown at 8 and when filtered is withdrawn from the filter elements 7 by means of the outlet pipes shown at 9 and 10, the pipes 9 all being connected with a single pipe shown at 11.

The lower longitudinal edge of the back plate 1 is also provided with a series of bearings shown at 12 to support a shaft 13, which shaft, together with the shaft 4, form a means for supporting and operating the locking structure proper. This locking structure comprises a series of locking members disposed side by side along the opposite longitudinal lines of jointure between the hood and back plate, the locking members themselves being rectangular in shape and designated by the reference numeral 14. As is indicated with more clearness in Fig. 6, these locking members have their longitudinal sides provided with slotted openings 105 16 through which the shafts 4 and 13 pass. The forward end of each of these locking members is provided with bolts 17 threaded into position and held in such position by means of lock nuts 18. These bolts are 110 themselves designed to engage the outstanding lugs 19 carried by the hood 6 along its

upper and lower edges. These locking members are actuated by means of toggles formed of toggle arms 20 rigidly keyed respectively to the shafts 4 and 13 and pivotally carrying at their forward ends, as indicated at 21, toggle links 22. These toggle links are also pivotally connected at their opposite ends by means of pins or bolts, as shown at 23, to the locking members and these pins further carry a roller 24 out to one side of the locking members, all after the manner illustrated in Fig. 11. These rollers are designed to coöperate with guard members 25 concentrically arranged with the shafts 4 and 13 and are located from these shafts a distance so that when the rollers 24 are in engagement therewith, the toggles will be maintained in an uncramped position.

20 The manner of operating these toggle locks is as follows: The shaft 4 is turned in a clock-wise direction and the shaft 13 in a counter clock-wise direction, which causes a slight turning of the toggle arms 20 and a consequent pull upon the toggle links 22. This breaking action of the toggles then causes a corresponding pull on the locking members 14 to move them out of clamping engagement with the lugs 19, which movement is permitted by means of the elongated openings 16. Further turning of these shafts will bring the rollers 24 into engagement with the inner faces of the guard members 25 to maintain these toggles in an uncramped position, although the main use for these guards occurs when the casing parts are being locked together rather than unlocked. However, this further rotation of the shafts then causes a swinging movement of the locking members 14 from the dotted position shown in Fig. 4, to the full line position. To lock the same, the shafts 4 and 13 are rotated in a reverse direction and, because of the guards 25, the toggles 20 will be maintained in an uncramped position so long as the rollers 24 are in engagement with their inner faces and this causes a return movement of the locking members 14 from the full line position of Fig. 4 to the dotted position in the same figure or until these locking members engage shoulders 26 located adjacent each of the lugs 19. As soon as the rollers 24 leave the guards 25, the toggles are again straightened out, since continued rotative movement of the locking members is prevented because of their engagement with these shoulders 26. This straightening of the toggles moves the bolts 17 into clamping engagement with the lugs 19 and as a result, the hood 6 is held in firm engagement with the back plate. In order that the toggle arm 20 will not pass by the center and again unlock the joint, I have provided the gear 29 with a stop pin 29^a, as is shown dotted in Fig. 1. This stop

pin is arranged to strike the upper edge of one of the end standards 2 when the toggle has been straightened out and in this manner, further rotation of the shafts 4 and 13 is impossible.

In order that the shafts 4 and 13 may be operated simultaneously, I have provided each of them with a lever 27 and pivotally connected the ends of these levers by means of the connecting rod shown at 28. The shaft 4 is also extended at one end to rigidly carry a gear 29 and loosely carry a hand wheel 30 whose hub 31 is formed to present a pinion, as is shown at 32. The gear wheel 29 is rigid with the shaft, while the hand wheel 30 and pinion 32 are rotatably mounted on the same. This pinion 32 meshes with a gear 33 suitably mounted on a shaft 34, which latter is held in position by means of one of the end standards 2 and the outstanding bracket shown at 35. The shaft 34 also rigidly carries a pinion 36, the arrangement being such so that rotation of the hand wheel 30 causes a rotation of the gear 33 because of its engagement with the pinion 32. In this manner the shaft 34 is rotated and consequently the shaft 4 is rotated very slightly compared with the speed of rotation of the hand wheel 30 by means of the driving connection between the gear 29 and the pinion 36. In order to hold the hood in any position of opening, I have formed a housing 37 on the underside of the bracket 35, a spring 38 being confined within this housing to retract a pin shown at 39. The lower end of this pin is operatively connected with the handle shown at 40, whose hub 41 is provided with a cam or inclined face, as shown at 42. The turning of the handle 40 from the position shown in Fig. 2, causes a retraction of the pin 39 against the tension of the spring 38. Return movement permits this pin to come into engagement with the teeth of the gear 36 and thus the hood is securely locked in any desired position.

In order to further lighten the load in opening the casing, I have provided each end of the casing with an upstanding arm 43, the upper ends of these arms being turned rearwardly, as shown at 44 a distance to support a counterweight 45 to the rear of the pivot connection between the hood and back plate. This counterweight is so arranged that it almost over-balances the weight of the hood itself and in order that the opening movement may be gotten by the turning of the shaft 4, as has been already related, I have also provided this shaft with a pair of outstanding levers 46 whose ends 47 are designed to engage the pin extensions 48 carried by each end of the counterweight, as is shown. It will be noted, however, that these arms are located some considerable distance away from the pins 48 and this ar-

angement is provided so that the locking members may be unlocked and swung out of a position of interference before the hood is given an opening movement.

- 5 From the foregoing, it will be apparent that I have provided a very efficient type of lock for holding the parts of the casing in their locked position. Also, this locking means may be manually operated and continued movement of the shaft 4 also causes an opening movement of the hood 6. This hood may be locked in any desired position of opening by means of the locking structure already referred to and this locking structure is supplemented by the locking effect produced between the gears and pinions.

What I claim, is:

1. A locking structure for a two-part filter casing, one of which is movable with respect to the other comprising a locking member adapted to lock the parts of said casing together, toggle lever means operable to first move said member to a locking position and then move it laterally into holding engagement with the casing, and means for keeping said toggle uncramped until said locking member has assumed a locking position.

2. A locking structure for a two-part filter casing, one of which is movable with respect to the other comprising a locking member adapted to lock the parts of said casing together, said member being formed with a slotted pivot opening, a pivot support coöoperating with said opening, and means whereby said member is swung about its support to assume a locking position and then moved laterally in the direction of the slotted opening into holding engagement with the casing.

3. A locking structure for a two-part filter casing one of which is movable with respect to the other comprising a pivotally supported locking member, and toggle lever means operable to first swing said member about its pivot into a locking position and then move it laterally into holding engagement with said casing.

4. A locking structure for a two part filter casing, one of which is movable with respect to the other, and means for locking said two parts together comprising a pivotally supported locking member carried by one of said parts and adapted to engage the other part, and toggle lever means for actuating said member to first move it laterally to release its holding engagement and then to swing it about its pivot away from said second named part.

5. A locking structure for a two part filter casing, one of which is movable with respect to the other, comprising a locking member carried by one of said parts and adapted to engage the other part, and toggle lever means for actuating said member to

first swing it into a locking position and then to straighten said toggle to bring it into clamping engagement with said second named part.

6. A locking structure for a two part filter casing, one of which is movable with respect to the other, comprising a locking member carried by one of said parts and adapted to engage the other part, toggle lever means for actuating said member to first swing it into a locking position and then to straighten said toggle to bring it into clamping engagement with said second named part, and means for keeping said toggle uncramped until it has assumed a locking position.

7. A locking structure for a two part filter casing, one of which is movable with respect to the other, comprising a shaft located parallel with one line of jointure of said parts, a locking member having a slotted opening by which it is supported on said shaft, said member being adapted to engage the movable part of said casing, a toggle arm rigidly carried by said shaft, and a toggle link pivotally connected at one end to said arm and at its other end to said member.

8. A locking structure for a two part filter casing, one of which is movable with respect to the other, comprising a shaft located parallel with one line of jointure of said parts, a locking member having a slotted opening by which it is supported on said shaft, said member being adapted to engage the movable part of said casing, a toggle arm rigidly carried by said shaft, a toggle link pivotally connected at one end to said arm and at its other end to said member, and a guard structure arranged to keep said toggle arm and toggle link uncramped until said member has been moved to a locking position with respect to said movable part.

9. A locking structure for a two part filter casing, one of which is movable with respect to the other, comprising a shaft located parallel with one line of jointure of said parts, a locking member having a slotted opening by which it is supported on said shaft, said member being adapted to engage the movable part of said casing, a toggle arm rigidly carried by said shaft, a toggle link pivotally connected at one end to said arm and at its other end to said member, a counterweight structure carried by said movable part, and an actuating connection between said shaft and said movable part arranged so said movable part is engaged for movement only after said locking member has been moved out of engagement.

10. A filter press comprising an upright back plate, a semi-oval hood member pivotally mounted to swing away from said back plate, shafts disposed adjacent the upper and lower lines of jointure of said plate and

hood, locking members each having a slotted opening by which they are supported on said shafts, a toggle arm carried by said shafts, a toggle link for each arm, said links being pivotally connected at one end to said arms and to said locking members at their opposite ends, and a driving connection between said shafts.

11. A filter press comprising an upright back plate, a semi-oval hood member pivotally mounted to swing away from said back plate, shafts disposed adjacent the upper and lower lines of jointure of said plate and hood, locking members each having a slotted opening by which they are supported on said shafts, a toggle arm carried by said shafts, a toggle link for each arm, said links being pivotally connected at one end to said

arms and to said locking members at their opposite ends, a driving connection between said shafts, upwardly projecting arms carried by said hood shaped to project rearwardly beyond the pivot support for said parts, a counterweight structure carried by the rearwardly projecting portions of said arms, and an actuating connection between said shaft and said hood, arranged so that said hood is engaged for movement only after said locking members have been moved out of locking engagement.

In testimony whereof I affix my signature in presence of two witnesses.

HERBERT N. KILBY.
